UNITED STATES PATENT OFFICE

HARRY KOPLIN, OF CHICAGO, ILLINOIS, ASSIGNOR TO THE AMICO COMPANY, INC., OF CHICAGO, ILLINOIS

DRYING MACHINE

Application filed February 1, 1930. Serial No. 425,270.

This invention relates to drying machines, more particularly to solvent reclaiming apparatus therefor, and has for its primary object to provide, in a manner as hereinafter set forth, an apparatus of such class by means of which solvents or cleaning fluids may be driven from drying clothes and condensed to permit the reuse of the solvent, thereby affording a means for removing a maximum 5 percent of the solvents from the clothes to render deodorizing of the clothes unnecessary, and further affording a means for reducing the expense of cleaning clothes with a solvent.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative rather than limitative, and that the invention is intended to be 10 limited only by the scope of the claims hereunto appended.

In the accompanying drawings in which like numerals are employed to designate like parts throughout the same:

Figure 1 is a sectional elevation of an embodiment of the invention.

Figure 2 is a top plan thereof.

Referring to the drawings in detail, the numeral 1 indicates a casing preferably supported on a plurality of oscillatory hanger links 2, the links being supported upon a plurality of spaced floor brackets 3. The brackets 3 may be of any suitable construction to swivelly support the links at the upper ends of the latter, the lower ends of the links being swivelly connected with the casing by means of a plurality of legs 4 projecting from the casing. The casing is open at its top with the exception of a flange 6 which projects inwardly from the upper edges of the sides.

The bottom 7 of the casing inclines upwardly toward the center and extending through the bottom, centrally thereof, is a bearing structure 8 for supporting a verti-

cally disposed shaft 9. Fixedly secured to the lower end of the shaft 9 is a pulley 10 which is driven by a belt 11 mounted on the drive pulley 12 of a motor 13.

Carried by the shaft 9 is a basket 14, the bottom 15 of which inclines upwardly towards the center and is fixedly mounted on the upper end of the shaft. The sides of the basket are perforated as indicated at 16 and the basket is open at its top with the exception of an inwardly directed flange 16 the inner edge of which is disposed in substantially the same vertical plane as the inner edge of the flange 5.

The casing 1 is provided with a lid 17 which is seated on the flange 5 and seated on the lid 17 is a heater shell 18. The shell 18 is provided in its upper wall with an opening 19 which is in registry with a similar opening formed in the lid 17. Mounted on the shell 18 is a motor 20, the shaft of which actuates a fan 21 disposed within the upper portion of the shell 18. Disposed within the shell 18, below the fan 21, is a steam coil 22, the opposite ends of which are connected with steam conduits 23, one of which provides an inlet and the other an outlet for the coil 22.

The conduits 23 are connected with pipe sections 24 of a steam supply system, not shown, the steam passing from one section to the other through the conduits 23 and coil 22. The sections are fixedly mounted on brackets 25 projecting from the upper face of the flange 5 and are disposed in longitudinal alignment with the conduits 23 loosely connected therewith whereby the sections provide the axis of a hinge mounting for the lid 17. The lid 17 is normally held in closed position by means of a clamp 26 carried by the flange 5 at a point substantially diametrically opposite the hinge mounting for the lid.

Secured to the lid 17 and extending at an upward inclination therefrom is a pair of cables 27 which pass over pulleys 28 mounted on supporting arms 29 secured to and projecting upwardly from the casing 1. Weights 30 are secured to the cables 27 whereby the cables 27 normally exert a force on the lid 17 to swing the same to open position. Adj-

cent the hinge mounting therefor, the lid 17 is provided with a pair of stops 31, the free ends of which abut against the upper face of the flange 5 for supporting the lid when the latter is in open position.

5 Adjacent the casing 1 is a condenser casing 31 having disposed therein a cooling coil 32. Having one end extending through the bottom 7 of the casing 1 is a vapor tube 33 which 10 enters the casing 31 adjacent the bottom of the latter and which is bent to provide a pair of oppositely disposed loops 34 and 35 arranged vertically within the casing 31. Mounted on the top of the casing 31 is a housing 36 for a motor 37 and suction fan 38, the latter being disposed directly over the outer end of the vapor tube 33 which opens through the top wall of the casing 31 at said outer end. If desired, the housing 36 may be provided with a suitable vent pipe, not shown. 15 On opposite sides of the upwardly extending loop 34 of the vapor tube 33, the latter is provided at its lowermost points with a pair of draw-off pipes 39 and 40.

20 25 The inner end of the tube 33 projects above the upper face of the bottom 7 of the casing 1 whereby any sediment within the casing will be prevented from passing into the tube 33, and spaced from the inner end of the tube 33, the bottom 7 is provided with a sediment trap 41 through which any sediment which collects within the casing 1 may be drawn off.

25 30 When clothes are being dried within the basket 14, steam is admitted to the coil 22 and air is driven by the fan 21 over the heated coil into the basket whereby the solvent with which the clothes are saturated is turned to vapor and drawn through the vapor tube 33 by means of the suction fan 38. As the vapor 35 passes through the tube 33 it is chilled by the proximity of the cooling coil 32 with respect to the tube whereby the major portion of the vapor is condensed and may be drawn from the tube 33 through the pipes 39 and 40 into 40 suitable receptacles 42.

45 It is thought that the many advantages of a solvent reclaiming apparatus in accordance with this invention will be readily apparent, and although the preferred embodiment of 50 the invention is as illustrated and described, it is to be understood that changes in the size, shape and arrangement of parts may be resorted to, so long as such changes fall within the scope of the invention as defined in the 55 appended claims.

What I claim is:

1. In combination, a clothes drying basket, a casing therefor, a heater arranged over the basket, a fan disposed over the heater for 60 forcing heated air through the basket to vaporize the solvent absorbed by the clothes therein, a condenser casing, a cooling coil within the condenser casing, and a vapor tube leading from the drying basket casing to the condenser casing, said vapor tube extending

through and projecting upwardly from the bottom of the casing for the drying basket, said bottom being provided with a sediment trap adjacent the projecting end of said tube.

2. In a clothes drier, an open top casing, 70 an open top clothes drying basket within the casing, a lid for the casing formed with an opening, a heater shell carried by the lid and surrounding the opening, a steam coil within the shell, longitudinally aligned pipe sections mounted on the casing, steam conduits connecting the coil with the pipe sections and having loose connection with the latter to provide a hinge mounting for the lid, a weighted cable connected with the lid and normally tending to swing the same to open position, and a clamp carried by the casing 75 for engagement with the lid to maintain the latter in closed position.

3. A drying apparatus comprising, an open top casing, a centrifugal extractor within the casing, a lid for the casing and formed with an opening, a heater shell carried by the lid and surrounding the opening, a steam coil within the shell, longitudinally aligned pipe 80 sections mounted on the casing, and steam conduits connecting the coil with the pipe sections and having loose connection with the latter to provide a hinge mounting for the lid.

4. A drying apparatus comprising, an open top casing, a centrifugal extractor within the casing, a lid for the casing, a heater element carried by the lid, longitudinally aligned heat conductor sections mounted on the casing, and heat conductors connecting the heater element with said conductor sections and having loose connection with the latter to provide a hinge mounting for the lid.

In testimony whereof, I affix my signature 95 hereto.

HARRY KOPLIN.
